UNITED STATES PATENT OFFICE.

F. S. STODDARD, OF LITCHFIELD, CONNECTICUT.

MACHINERY FOR SPINNING WOOL.

Specification of Letters Patent No. 12,532, dated March 13, 1855.

To all whom it may concern:

Be it known that I, FREDERICK S. STODDARD, of Litchfield, in the county of Litchfield and State of Connecticut, have invented certain new and useful Improvements in Machinery for Spinning Wool, a Mixture of Wool and Cotton, or other Fibrous Materials; and I do hereby declare that the following is a full, clear, and exact 10 description of the same, reference being had to the accompanying drawings, forming part of this specification, in which—

Figure 1 is a vertical section of a spinning frame constructed according to my invention. Fig. 2 is a plan of the principal parts of the same. Fig. 3 is a front view of the countertwist pulleys and one pair of front drawing rollers. Fig. 4 is a front view of a bridge for giving an angular direction 20 to the roving during its drawing or reduction.

Similar letters of reference indicate corresponding parts in the several figures.

This invention is particularly applicable 25 to the spinning of wool alone, or a mixture of cotton and wool, but it may also be applied to the spinning of such other fibrous materials as it may be suited for. It consists in certain means of governing the counter- 30 twist whereby the roving is allowed to receive very little twist near the back drawing rollers where it is full size, but to receive an increasing twist as it approaches the front drawing rollers and is reduced by drawing, 35 and in certain means of producing friction or drag upon the ring traveler at some part of every revolution while winding on the larger part of the cone, and relieving it of such friction or drag in winding on the 40 smaller parts, whereby an uniform or nearly uniform tension is produced upon the thread at all stages of the winding.

To enable those skilled in the art to make 45 and use my invention I will proceed to describe its construction and operation.

A, is the framing which supports all the working parts of the machinery.

B is the main shaft, B', the main cylinder, and C, the counter cylinder.

50 D, D, are the back drawing rollers, and E, E, the front drawing rollers; the former of which are of the kind commonly employed, but the latter differ from those commonly employed as will be hereinafter 55 described.

F, F, F, are the countertwist pulleys, which perform the twist by means of their peripheries. These pulleys consist each of a short cylinder of metal with a band z, of woolen cloth around its periphery. They 60 are secured upon parallel axles a, a, a, which are placed at right angles to the axles of the drawing rollers, and parallel to the roving, as it passes from the back to the front drawing rollers, being at those ends of the 65 axles next the front drawing rollers; and their peripheries just touch each other lightly. They are caused to revolve all in the same direction by bands b, from the cylinder C, running over pulleys c, c, c, on 70 their axles and each roving passes between two of them at or near their point of contact and receives the twist in consequence of the contiguous portions of the rollers moving in opposite directions. The bearings of the spindles a, a, are in bridges H', H', secured to the top of the framing A.

The front drawing rollers E, E, E', E', are placed so close to the fronts of the countertwist pulleys as nearly to touch 80 them. The bed rollers E, E, are covered and are made of about the usual diameter of covered drawing rollers, as covered rollers can not well be smaller, but the top rollers are fluted and made much smaller—not 85 more than half the diameter—in order that they may get their bite as close as practicable to the countertwist pulleys, or nearer thereto than the length of the fibers. The journals of the bed rollers work in fixed 90 bearings e, e, and receive rotary motion by a belt which is not shown in the drawings. The top rollers have their journals working in bearings in the ends of levers G, G, which work on fixed fulcra d, d, in brackets 95 f, f, secured to the framing. These levers have weights g, g, suspended from them between their fulcra and the top rollers, in order to draw the top rollers down upon the bed rollers and give them sufficient bite. 100 The top rollers receive motion from the bed rollers by their contact. Instead of hanging each top roller in a separate lever G two may be attached to the same lever, one on each side.

H, Figs. 1, 2, 4, is a bridge extending the whole length of the frame between the front and back drawing rollers, about midway between them or nearest the back rollers, carrying fingers h, h, of which there is one 110

for each spindle of the spinning frame, for the purpose of regulating the counter-twist and preventing too great a degree of twist getting back to the large part of the 5 roving near the back drawing rollers, which is done by the fingers giving an angular direction to the roving as illustrated in Fig. 1, where the roving is represented in red color passing over the finger. The bridge is 10 supported at its ends upon the framing by screws *i*, *i*, by which it can be adjusted higher or lower, and the fingers are adjustable separately, being each attached to the bridge by a pivot *s*, at one end see Fig. 4, 15 and having not far from the said pivot a female screw, receiving a male screw *j*, which rests upon the bridge and serves to raise or lower the finger. By carrying the roving in an angular direction over the 20 finger *h*, too much twist is prevented passing the said finger toward the back rollers, and the twist is caused to be gradual and to increase in about the same proportion as the roving is reduced by drawing, which 25 is the true principle to be observed in wool spinning. Without this bridge the counterclockwise would extend into the full sized roving to such an extent as to prevent its drawing easily and regularly. The twist 30 can be regulated with great nicety by the adjustment of the bridge and fingers before spoken of to increase or diminish the angle in the roving; the increase of the angle having the effect of further preventing the 35 counterclockwise extending back into the large part of the roving, and the diminution of the angle having a contrary effect.

The angular direction may be given to the 40 roving either downward or laterally instead of upward as shown, by proper arrangements of a bridge and fingers or some devices equivalent thereto. In order that in starting or after mending the roving, it may receive a partial twist to enable it to 45 bear being drawn in the angular direction, a sufficient space is left between the fingers and the bridge, by following the bridge as shown at *k*, *k*, in Fig. 4, or otherwise to allow the roving to be conducted directly 50 from the back to the front rollers, as shown dotted in red color in Fig. 1. As soon as sufficient twist is given, it merely requires to be passed by hand over the end of the finger on to the top.

55 *l*, *l*, are the spindles driven as usual by bands *m*, from the main cylinder, *n*, *n*, are the bobbins, *I*, is the ring plate, and *o*, *o*, are the ring travelers all of the usual construction. The ring plate is operated upon 60 to lay the cones on the bobbins in a well known manner by a lever *J*, and a cam *K*, on a shaft *M*, see Fig. 1; the lever being varied to vary the ring plate by means of a screw *L*, carrying a nut *N*, to which the

lever is attached; and the said screw receiving a constant rotary motion through a band *p*, from a pulley on the shaft *M*. A drag is produced upon the ring travelers when winding on the large part of the cones, by means of a series of brushes *q*, *q*, which 70 are secured by binding screws *r*, *r*, in sockets *s*, *s*, in a beam *O*, which extends the whole length of the frame and is hinged at each end or at proper intervals by hinges *t*, *t*, to the back of the ring plate. One of 75 the brushes stands opposite every ring *u*. The beam *O*, has a small eye *v*, at the back near one end, which receives a rod *w*, standing up rigidly from a lever *P*, one end of which works on a fixed fulcrum *x*, attached 80 to the framing and the other receives a screw *y*, which rests upon a cam *Q*, on the shaft *M*. The lever *P*, receives a vibrating motion from the cam, and the rod *w*, is thereby caused to impart a vibrating motion 85 to the brush beam *O*. The cam *Q*, is so arranged relatively to the cam *K*, that as the ring plate rises the brushes *q*, *q*, will fall back from them, and as the plate descends, the brushes advance toward the rings. The 90 brushes are so adjusted by the screwing up or down the screw *y*, in the lever *P*, that when the ring plate descends and the winding is being performed on the lower part of the cone, the travelers will during their 95 revolutions come in contact with and receive a drag from the ends of the brushes. As the ring plate rises and the brush beam falls back, this drag will be diminished and finally before the rail reaches the top of its 100 movement the brushes will leave the traveler quite free. By thus producing a drag on the travelers while winding the large part of the cone, the tension on the thread, and the tightness of the winding may always be 105 rendered uniform, but without such drag an uniform tension cannot be kept up, as the traveler will run so much easier while winding the large part than while winding the small part of the cone. The tension may be 110 regulated exactly by the screw *y*, in the lever *Q*. Instead of the brushes *q*, *q*, pieces of leather or other soft or elastic material may be used.

The method of regulating the tension of 115 the thread during the winding enables a larger bobbin to be used and prevents breakage.

What I claim as my invention and desire to secure by Letters Patent is—

1. Conducting the roving from the back to the front drawing rollers by employing a bridge (or rest) with fingers upon it situated between the front and back pairs of drawing rollers for the purpose of governing the counter twist, so as to adapt a smaller portion of it to the part of the 125 thread nearest the back rollers.

2. Impeding the ring travelers while winding upon the lower or larger parts of the cones by means of a series of brushes q , q , or their equivalents operating substantially as set forth so as to gradually set the travelers free as the winding approaches the smaller or upper ends of the cones, thereby producing an uniform tension on the thread while winding.

FRED'K S. STODDARD.
